T. J. FRAZIER, OF ST. PAUL, MINNESOTA.

Letters Patent No. 73,793, dated January 28, 1868.

IMPROVEMENT IN HEATING-STOVES.

The Schedule referred to in these Letters Patent and making part of the same.

TO ALL WHOM IT MAY CONCERN:

Be it known that I, T. J. FRAZIER, of St. Paul, in the county of Ramsey, and State of Minnesota, have invented new and useful Improvements in Stoves; and I do hereby declare that the following is a full, clear, and exact description thereof, which will enable others skilled in the art to make and use the same, reference being had to the accompanying drawings, forming part of this specification.

This invention relates to improvements in stoves, and consists in an arrangement of a bulk-head and of flues, over and through which the products of combustion are led, giving a much greater radiating surface combined with less consumption of fuel than in the form of stove heretofore used. In the accompanying drawings—

Figure 1 shows on the left side a front elevation with part of the casing broken away, and on the right a section on the line xx of fig. 2, of my improved stove; and

Figure 2 is a longitudinal section thereof, on line yy of fig. 1, with part of the inner lining broken away to show flues and smoke-chamber.

Similar letters of reference indicate like parts.

A is the front of the stove; B, the bulk-head open beneath, the products of combustion passing over B into the chamber C, and thence, in the direction of the arrows, through the flues D, set outside the side walls of the stove into the up-take or smoke-stack E. F is a hole for cleansing the flues. There may be one in each up-take or one to each flue, as preferred. G is a damper, to admit of the heat being radiated downwards. H and H' are dampers in front of the stove, to increase or diminish the draught, and I the door for lighting, adding fuel, cleaning, and other purposes. The up-take E may be replaced by any other form of outlet for the products of combustion.

I claim as new, and desire to secure by Letters Patent—

The combination of the flues D, up-take E, and bulk-head B, substantially as described, or their respective equivalents, with a stove, as herein set forth.

T. J. FRAZIER.
